Term of patent 14 years

(Cl. D34—5)

FIG. 1

FIG. 2

FIG. 1 is a plan view of a game board showing my new design; and

FIG. 2 is a cross-sectional view taken through line 2—2 of FIG. 1.

The characteristic feature of my design resides in a rectangular game board surrounded by a raised rail, said game board having a hexagonal raised playing surface thereon, said playing surface having three circular depressions along the transverse medial line of said surface and a guide line adjacent each of said opposed ends of said hexagonal shaped raised playing surface.

I claim:

The ornamental design for a game board, substantially as shown and described.
